IMPROVEMENT IN STOP-MOTION FOR LOOMS.

ALEXANDER CARMICHEL AND WILLIAM BARNEY, OF WESTERLY, RHODE ISLAND, AS-SIGNORS TO THEMSELVES AND COTTRELL & BABCOCK, OF THE SAME PLACE.

Letters Patent No. 59,962, dated November 27, 1866.

SPECIFICATION.

TO ALL WHOM IT MAY CONCERN:

Be it known that we, ALEXANDER CARMICHEL and WILLIAM BARNEY, of Westerly, in the county of Washington, State of Rhode Island, have invented certain new and useful improvements in Stop-Motions for Looms; and we do hereby declare the following is a full and exact description thereof.

Our invention consists in mechanism whereby the belt is shipped off the driving-pulley, and a positive stop interposed to arrest the motion of the loom by the same automatic movement; and in arrangements of the details which make the same more efficient and convenient.

Stop-motions have long been considered necessary, the purpose being to stop the action of the loom whenever the filling-yarn breaks. In some varieties of weaving, no particular harm results, excepting the loss of time, when the shuttle flies idly across, and all the mechanism of the loom continues to act with its proper motions; while, in consequence of there being no filling introduced by the traversing of the shuttle, no weaving is performed. But in other varieties of looms, those adapted to weaving checks or figures, for example, the evil becomes very great, by reason of the disturbance and confusion thereby introduced in the weaving of such work.

The stop-motions in general use are of two kinds. The first is a positive stop, arresting the motion of the machinery by interposing a sudden check, as by suddenly locking the driving pulley, or some other principal part. With such, the mechanism is strained, and the belting, etc., subjected to more or less injury by being compelled to slip on the driving pulleys. The other form of common stop-motion simply ships the belt off the driving pulley, and this relieves the mechanism, belting, etc., from strain; but with such, the action of the loom is not instantly arrested, and the few revolutions, or partial revolutions, of the loom after the shipper has moved, may be sufficient to produce serious difficulty. Our invention, by simultaneously moving the shipper, and positively arresting the motion, avoids these faults of the ordinary stop-motions, reduces the labor of attending looms, reduces the quantity of waste produced, and makes a better cloth.

We will first proceed to describe our invention, and will afterwards designate the points which we believe to be new. Accompanying drawings form a part of this specification.

Figure 1 is a side elevation; and

Figure 2 a plan view of a loom with our improvements.

Similar letters of reference indicate like parts in both figures. The drawings represent the novel parts, with so much of the other parts as is necessary to indicate their relation thereto. The material may be of the ordinary kinds. The novel parts may be iron.

A is the fixed framing of the machine, B is the crank, and C the connection which gives motion to the lay, D, which latter is adapted to vibrate on the centre, d, as usual. D¹ is the reed, D² the shuttle-race, and M the cloth. E is a shaft which turns with half the velocity of the crank shaft, B; and E' is a cam fixed thereon, which consequently revolves once while the crank, B, revolves twice. F is the long arm, and F' the short arm of a lever which vibrates on the centre, f, and is actuated by the cam, E'. G is a loose lever mounted on the same centre, f, and g is a light lever nearly balanced on the lever, G, just described, being pivoted thereon at the point, g'. At each revolution of the shaft, E, the lever, F F', is operated, throwing the arm, F', powerfully to the left, looking at the drawings, and returning. The light lever, g, formed as represented, hooks over the end of the arm, F', and holds thereon with such force as to compel itself and the connected arm, G, to be also carried forward, that is, toward the left, in our figures, with the arm, F', unless it has previously felt the thread of the filling, which stretches across the space where the lighter end of the lever, g, is presented. In all ordinary cases, the lever, g, touches the filling thread and is tilted so that the arm, F', when it makes its forward movement, produces no effect; but the moment the filling breaks, it ceases to tilt the lever, g, and, consequently, the lever, g, and the connected arm, G, under such circumstances are moved forward. So far as yet described, the mechanism is old. The forward movement of the arm, G, thus taking place only at the time when the filling is broken, has long been employed to set in motion the additional mechanism which stops the loom. The additional mechanism hereinafter described contains novelty. H is a lever pivoted to the framing at the point, h, and adapted to be struck and turned by the forward movement of the arm, G. I is a lever provided with a convenient handle, I', at its top, and attached to the framing by a spring connection, i, below, so that it is adapted to allow a slight motion by its elasticity. J is a hook fixed in the frame at the point represented. K is a slide mounted as represented, in the housings, k k, and bent as represented; the long arm, K', receiving the pressure of the strong spring L, fixed on the frame at the point, l, and which tends to move the arm, K', outward from the framing of the loom, it being restrained only by its contact with the lever, I, before described. On the other extremity of the

slide, K, is a short arm, K², projecting horizontally toward the lay, D. This arm, K², forms a positive stop for the lay by striking the pin, *, which projects forward from the lay, D. When the slide, K, is in its usual condition, and the loom is working satisfactorily, the arm, K², stands out of the path of the pin, *, and produces no effect. But when, in consequence of the absence of the filling thread, the lever, H, is turned as above described, it pushes the lever, I, out of contact with the hook, J, in which condition it offers no resistance to the motion of the slides, K, which immediately moves outward, in obedience to the spring, L. This movement puts the stop, K², directly in the path of the pin, *, so that as the lay, D, moves forward, the pin, *, strikes the arm, K², and arrests the motion. P is a lever pivoted to the frame at the point, p, it is provided with two forks. The fork, P¹, embraces the lever, I, and the fork, P², embraces the belt, Q, which is the driving belt. When the loom is working satisfactorily, the lever, I, being held close to the framing of the loom, by being held within the hook, J, the fork, P², stands in such position that the belt, Q, runs on the fast pulley, R, and maintains the proper motion of the loom. At the moment the filling thread breaks, and induces the series of movements above described, the outward motion of the arm, I, turns the lever, P, on its centre, p, moving the fork, P¹, outward from the framing of the loom, and moving the opposite fork, P², inward toward the bed of the loom. This causes the fork, P², to act as a belt shipper, and transfer the belt from the fast pulley, R, to the loose pulley, R', and allows the belt to turn the loose pulley, R', idly, without imparting any motion to the loom or inducing any friction or strain on the parts. P³ is an additional arm on the same lever, P. It stands in such position that it is of no effect while the loom is working satisfactorily; but the moment the lever, I, moves outward as described, and turns the lever, P, on its centre, p, the arm, P³, is placed in such position as to meet the crank, B, and to thereby arrest the motion of the loom. It will be observed that this arm, P³, forms an additional positive stop to the loom, so that with all the parts here described, the breaking of the thread induces; first, the simultaneous putting in position of two positive stops to the motion of the loom, the arm, K², striking the pin, *, on the lay, D, and the arm, P³, striking the crank, B; and second, the movement of the belt shipper, P², so as to shift the belt off the driving pulley. I can, as above intimated, dispense with one of the positive stops, P³, or K², when the other is in good condition, so as to be perfectly reliable. All the parts are instantly placed in a condition for weaving again by the attendants simply grasping the handle, I', and moving it inward toward the frame, and drawing it forward into the hook, J. This movement ships the belt onto the driving pulley, R, and removes both the positive stops out of the way, so as to no longer obstruct the motion of the loom; and it at the same time places all the parts in a proper position to be again operated whenever the filling thread breaks. I provide the handle, K³, for convenience in sometimes moving the slide, K, to allow of turning the loom by hand before touching the handle, I. We do not confine ourselves to the employment of both the positive stops, the one acting against the lay, D, and the other against the crank, B, as we believe either may be used with good effect without the other, but in such cases we prefer to retain that portion of the mechanism which directly arrests the action of the lay, D. It is not essential to the success of our invention that the positive stop shall be a slide. A lever, or any other convenient modification of such device, may be employed in lieu of the slide if preferred; the purpose being to simply provide a movable part of sufficient strength, and easily moved, so as to be readily thrown into position, to arrest the motion, by the action of a spring, or an equivalent weight, or the like, at the time when the absence of the filling thread shall call for it. Some of the advantages due to certain features of our invention may be separately enumerated as follows:

First, by reason of the fact that a positive stop is introduced to arrest the motion of the loom at the same moment the shipper is moved, we are able to insure that the belt shall be placed in a position for being immediately slipped off the pulley so as to greatly diminish the strain thereof; while at the same time the action of the loom is positively and instantaneously stopped, so that there can be no possibility of another throw, or partial throw of the shuttle. This avoids the necessity for picking out threads, setting the motion of the loom back, readjusting, etc., in case a jacquard, or other delicate mechanism is employed to produce figures, checks, or the like; saves the wear of belting, and the loss of motive power, and weaves a better fabric.

Second, by reason of the fact that the stop, K², arrests the motion of the lay, we are able to insure that no springing of the mechanism, or other cause, shall allow the lay to advance so far as to strike the shuttle, if the shuttle lies in the shed.

Third, by reason of the fact that we arrange the slide, K, near the top of the beam, and provided with a handle K³, or its equivalent, for conveniently moving it by hand, we promote the convenience of the operator by making it easy to observe its position, and easy to change it by hand, so that the loom may be turned by hand and perform one or more revolutions in that manner before the belt is shipped on the pulley, and power weaving begins.

Having now fully described our invention, what we claim as new therein, and desire to secure by Letters Patent, is as follows:

1. We claim the combination, with a loom, of a belt-shifting motion and positive stop, arranged for joint operation, substantially as and for the purpose herein specified.
2. We claim arranging a positive stop in such combination, that it shall act against the lay of the loom, substantially as and for the purpose herein specified.
3. We claim the within-described arrangement of such positive stop in combination as specified, in sight and within convenient reach of the operator, and providing it with a handle K³, or its equivalent, so that it may be more easily placed by hand in such position as to allow the loom to be operated freely by hand, all substantially as and for the purpose herein specified.
